UNITED STATES PATENT OFFICE.

JOHN EDWARD THORNTON, OF WEST HAMPSTEAD, LONDON, ENGLAND, ASSIGNOR TO
JOHN OWDEN O'BRIEN, OF MANCHESTER, ENGLAND.

PHOTOGRAPHIC-PRINTING PROCESS.

1,408,313.

Specification of Letters Patent. Patented Feb. 28, 1922.

No Drawing. Original application filed March 21, 1916, Serial No. 85,702. Divided and this application filed July 8, 1919. Serial No. 309,426.

To all whom it may concern:

Be it known that I, JOHN EDWARD THORNTON, a British subject, residing at West Hampstead, London, England, have invented 55 certain new and useful Improvements in and Relating to Photographic-Printing Processes, of which the following is a specification.

This invention relates to the production 10 of kinematograph films.

The object of the invention is to prepare a printing belt or belts by which transparent kinematograph films of indefinite length can be produced by mechanical printing of the 15 pictures thereon with applied inks or colours as distinct from printing photographically with sensitive chemical media acted upon by light and as distinct from applying colour to a photographically printed series 20 of pictures.

The original picture film of indefinite length is photographed in the ordinary way and from this the one or more printing belts are prepared by any of the processes known 25 in photo mechanical printing as intaglio in which a series of fine indentations or pits are formed to receive the ink or colour and may be termed ink wells or pits and from which the ink or colour is transferred to the surface 30 of the transparent kinematograph film of indefinite length.

Photo mechanical printing is defined as follows:—The actual operation of printing requires neither the use of a sensitive surface nor the action of light, nor subsequent 35 development. Instead of such methods printing is effected by mechanical pressure of the film against a plate (in the form of a continuous belt) which has been prepared 40 with a series of images by one of the photo mechanical processes.

The medium used to form the image is therefore a printing or applied ink or colour instead of a sensitive salt. Various 45 kinds of inks or colours can be used according to the particular type of engraved or other printing plate (herein termed "printing belt") used.

I prepare a strip or band of copper, steel, 50 brass, aluminum or other metal, or a strip of gelatine, the gelatine being on a supporting base, or a strip of celluloid with a coating of

gelatine or other colloid prepared with a sensitive surface in any of the methods well known for photo mechanical printing to receive an impression of the original picture film.

The prepared strip which is to form the printing belt is perforated or notched along its margins to correspond precisely with the 60 perforations or notches in the camera film and in the transparent kinematograph film of indefinite length.

Upon the prepared strip I prepare a mechanical printing surface (hereinafter referred to as a printing belt) comprising a number of fine indentations or pits to contain and transfer ink or colour, by photographically forming thereon from the original picture film through a screen as herein-after described. The gradations of light and shade are produced by depositing varying quantities of ink by the varying size or capacity of the ink pits or wells either by varying the size or area thereof whilst maintaining a uniform depth or varying the depth whilst maintaining a uniform area, or by varying both area and depth and also by varying their distance apart.

The printing belt is engraved in intaglio 80 by the processes known as photogravure, intaglio or reversed half tone. The images for this process are produced by the same means (merely reversed) as used for preparing an engraved relief belt. Ink or colour is applied to the intaglio image by a plush roller that completely fills the indentations or pits, and the surplus is wiped off the surface of the belt by a scraper, leaving the indentations filled to the top with ink, which is afterwards transferred to the film by pressure.

In preparing printing belts from the original picture film more particularly of the individual elemental colours two or more of such printing belts may be made from 95 each, one lightly exposed for the dense parts and the other fully exposed for the lighter tones. By printing from one or other of these printing belts or from both in succession a high degree of tint is reached and 100 desirable or special effects for harmonizing harshness or other defects becomes practicable. Or one of such printing belts may be used for printing say a light shade or

tone of blue or a greenish blue, and another for printing a deep blue or a purple blue to give better effect to the colours in the picture. This mode of operation is regarded 5 as of special importance in relation to originals produced by the two-colour process.

The printing belt is made of a strip of continuous indefinite length of metal, celluloid or other material with the pictures 10 etched thereon in intaglio by well known methods, or any one of the published and current procedures for making an intaglio printing surface.

A process for forming a printing surface 15 of actual hardened gelatine is the Leimtype of Husnik which is briefly described on pages 330 and 331 of *Cassel's Cyclopaedia of Photography* published in 1912, and further a description is given in Husnik's British 20 specification No. 37 of 1887. To obtain the most satisfactory results by the Leimtype process certain improvements and modifications are desirable and these as hereinafter described must be regarded as a part of the 25 present invention. The film base is a flexible band of metal, celluloid or other material grooved or perforated to promote the adhesion of the gelatine with which it is coated, this coating being on one side or 30 both, and the gelatine having been sensitized and printed and treated in accordance with the Husnik method gives a grained typographic surface, but when an intaglio surface is required the exposure should be under 35 a lined or grained diapositive.

A printing belt having a base of celluloid 40 is coated with a sensitized resist (as for example bichromated fish glue) similar to that used on metal for ordinary process work. I print upon it from the original picture 45 film and after exposure, followed by washing out in the usual way, the celluloid is etched by an air blast or a sand blast charged with a solvent of celluloid such for example as amył-acetate.

In the preparation of the printing belts when printing through the screen it is desirable that the screen should be moved slightly—relatively to the belt—either laterally or longitudinally or both after each 50 individual picture is exposed so that the indentations or pits in the printing surface of the printing belt and subsequently the dots or points or lines printed therefrom 55 upon the kinematograph film will not fall in the same place in the successive pictures and so owing to the rapidity of projection and the persistence of vision such dots or points will not be visible on the enlargement 60 when projected upon a sheet or screen, the pictures appearing as a full tone grainless picture.

The kinematograph film.—The strip or film upon which the pictures are to be printed 65 from the printing belts to produce the

finished kinematograph film may be of the ordinary celluloid material now employed for kinematograph films or any other transparent film material.

Mechanical printing of kinematograph films.—In the mechanical printing of the films from the printing belts herein described any suitable printing ink or colour may be employed that is adapted to the particular form of printing belt and the surface 75 of the film upon which the print is to be made.

The printing may be done by applying the ink to the printing belts by any well known printing method such as by a roller, and removing the excess by a doctor or knife. The printing belts with perforations along the margins in which registering pins can operate and the film also similarly perforated along the margins are drawn together 80 between rollers or pressing surfaces by which contact or pressure will be applied 85 picture by picture. Sprocket teeth or claws are fitted to draw the two through the machine in correct register.

What I claim as my invention and desire to protect by Letters Patent is:—

1. A photo mechanical printing belt of continuous indefinite length for the production of continuous indefinite lengths of 90 transparent kinematograph positive film pictures, provided with perforations in the margins accurately spaced and a series of printing clichés formed on the surface and having pictures arranged in succession longitudinally thereon, each cliché being capable of printing a half tone image with all the gradation of a photograph, the cliché consisting of a large number of broken tone markings comprising intaglio pits forming 100 ink wells, and the gradation of image being formed by making the said pits of varying capacity per unit of area so that they are capable of depositing varying quantities of 105 ink, and thus forming a series of printed 110 images of full gradation by the agency of applied ink and pressure.

2. A series of photo mechanical printing belts of continuous indefinite length for producing continuous indefinite lengths of 115 transparent kinematograph positive films as in claim 1, for printing the main part of each image by one intaglio printing belt, and intensifying parts of each image by printing from another intaglio printing belt 120 or belts, the corresponding parts of each image of the series being different in the quantity of ink deposit for each belt, and requiring the printing from all belts in succession to complete the series of images and 125 to differently intensify each image of the series.

3. A series of perforated photo mechanical printing belts for producing continuous indefinite lengths of kinematograph positive 130

films by means of half tone intaglio ink pits of varying capacity per unit of area, as in claim 1, the said ink pits having their incidence varied in relation to the particular part of the picture image upon every printing belt of the series, in order that the grain of the picture may be obliterated by the successive printings, and thus form a series of full tone grainless film pictures 10 by applied ink and pressure and superimposed printings.

4. A series of perforated photo mechanical printing belts for producing continuous lengths of kinematograph positive prints in 15 multi-colour heliochrome, by means of half tone intaglio ink pits of varying capacity per unit of area as in claim 1, each colour of the composite heliochrome being formed upon a separate belt, which colors are subsequently 20 printed on to the film by superimposed printing, and by applied ink and pressure, to produce complete heliochrome continuous positive films.

5. A series of perforated photo mechanical printing belts for producing continuous lengths of kinematograph positive prints in 25 multi-colour heliochrome, by means of half tone intaglio ink pits of varying size and area as in claim 1, the composite heliochrome 30 being split into a plurality of printings of each colour and each being printed from a different belt in which the ink pits have their incidence varied in relation to the same particular part of the picture image, 35 in order that the grain of one printing may be obliterated by the second printing of the same section of the picture, with the object of producing, when the remaining colours of the image series have been similarly split 40 and applied, a series of grainless full tone heliochrome kinematograph positive film pictures, by applied ink and pressure and superimposed printings.

6. A continuous printing belt as in claim 1, having its printing cliches produced by 45 intaglio methods, in a series of ink-holding pits of varying capacity per unit of area depth, which receive varying quantities of ink according to their varying capacity, and yield it to an absorbent film surface by means 50 of applied pressure.

7. A continuous intaglio printing belt, as in claim 6, having its surface grooved to promote adhesion to the cliches formed on its face and prevent their tearing off during 55 inking and printing.

8. A continuous printing belt for direct printing on to a continuous kinematograph film as in claim 6, prepared with pit-like 60 intaglio images by the improved Leimtype method substantially as described.

9. A photo mechanical printing belt of continuous indefinite length provided with perforations in the margins and having 65 formed thereon by photo-chemical means a series of printing cliches having pictures arranged in succession longitudinally thereon, each composed of a large number of intaglio ink pits, the gradation of each image being formed by making the said 70 ink pits of varying capacity to render them capable of depositing varying quantities of ink to form pictures, in the form of a continuous series upon a continuous indefinite length of kinematograph film, and the ink 75 pits in each succeeding cliché of the series staggered in relation to those of the adjacent cliches.

In testimony whereof I have hereunto set my hand in presence of two subscribing 80 witnesses.

JOHN EDWARD THORNTON.
